CLAIM

The ornamental design for a cabinet door locking device, as shown and described.

DESCRIPTION

FIG. 1 is a perspective view of a design for a cabinet door locking device;

FIG. 2 is a front view of the design seen in FIG. 1;

FIG. 3 is a rear view of the design seen in FIG. 1;

FIG. 4 is a left side view of the design seen in FIG. 1;

FIG. 5 is a right side view of the design seen in FIG. 1;

FIG. 6 is a top view of the design seen in FIG. 1; and,

FIG. 7 is a bottom view of the design seen in FIG. 1.
